Attorney

UNITED STATES PATENT OFFICE.

THOMAS McCULLOUGH, OF MEDICINE LODGE, KANSAS.

IRONING-BOARD.

1,314,411.

Specification of Letters Patent. Patented Aug. 26, 1919.

Application filed March 16, 1918. Serial No. 222,889.

To all whom it may concern:

Be it known that I, THOMAS McCULLOUGH, a citizen of the United States, residing at Medicine Lodge, in the county of Barber and State of Kansas, have invented 5 certain new and useful Improvements in Ironing-Boards, of which the following is a specification.

This invention relates to new and useful 10 improvements in ironing boards and the primary object of the invention is to provide an ironing board that is portable said board being provided with depending supports that when inoperative are adapted to 15 be folded beneath the board, but when operative, swing down and are interengaged to securely support the board in operative position.

Another object of the invention is to provide 20 a portable ironing board of this character that is provided adjacent one end with a pivotally connected iron holder stand that is swingable in a horizontal plane, and which is provided with a guide portion said 25 stand being adapted when not in use to swing beneath the board, but when operative swings outwardly adjacent one side thereof to support an iron.

A further object of the invention is to 30 provide a portable ironing board of this character that is provided with a supplemental smaller board adapted to be superposed thereover, said small board being pivotally connected with the main board, so that it is 35 adapted to swing outwardly when not in use.

With these and numerous other objects in view, my invention consists of the novel features of construction, combination and arrangement of parts which will be herein referred to and more particularly pointed out 40 in the specification and claim.

In the accompanying drawings:

Figure 1 is a side elevation of the ironing 45 board in operative position,

Fig. 2 is a rear elevation of the board, and

Fig. 3 is a vertical section through one 50 end of the board showing the connection of one of the supporting members and supplemental board therewith.

In describing my invention I shall refer 55 to the drawings in which similar reference characters will designate corresponding parts throughout the several views.

The numeral 1 designates an ironing board of conventional size and shape which is provided at one end thereof with a projecting portion 2 that has its end provided with a pair of parallel slots 3 therein for 60 a purpose to be hereinafter more fully described. The ironing board is provided with a pair of hingedly connected oppositely swingable supports, designated by the numerals 4 and 5 the support 4 being longer 65 than the support 5 and when operative extending beneath the board from one end to the other. This supporting member or leg is pivotally connected with the projecting end 2 of the board by means of a U-shaped 70 bracket 6 that has its opposite side portions positioned through the slots 3 in said end, with its face resting upon the upper surface thereof, as is clearly shown in Fig. 3 of the drawings. The end of the supporting 75 leg 4 is pivoted between the sides of the bracket 6 and this pivoted connection designated by the numeral 7 will be positioned beneath one end of the board 1. The leg 4 is swingable upwardly beneath the under 80 surface of the board 1 when inoperative, as will be hereinafter more fully described.

The supporting member 5 is formed of a pair of depending legs 8 which are hingedly connected at their upper ends as shown at 9, 85 with the lower surface of the board at a point adjacent the end to which the first mentioned supporting leg is connected. These depending legs 8 are connected by a cross strip 10 said strip being preferably 90 formed of metal and adapted to fit into a socket 11 formed in the upper face of the leg 4 when the parts are in operative position, as is clearly shown in Fig. 1 of the drawings. This cooperative engagement between 95 the supporting legs together with the fact that they are so mounted that they are adapted to swing oppositely, forms a very secure connection and support for the board 1.

The board is additionally supported by a hinged brace 12 that is hinged as shown at 13 to the under surface of the board 1 adjacent the outer end thereof, the lower end of said brace being adapted to fit into a 105 socket 14 in the upper face of the leg 4 when the said leg is in operative position. This connection is clearly shown in Fig. 1 of the drawings. The under surface of the board 10 is provided with a spring clip 15 that is of 110

sufficient size to securely clamp the brace and leg 4 therebetween when the device is inoperative, as will be hereinafter more fully described.

I have provided an iron holding attachment which comprises a pivoted stand 16 that is connected with the undersurface of the board 1 adjacent the inner end thereof, said stand being swingable horizontally, and 10 adapted to be positioned either beneath the board 1 or projecting from the edge thereof to support an iron thereon. This stand is circular with a projecting portion that extends beneath the board and is pivotally 15 connected therewith as shown at 17 in Fig. 2 of the drawings. The movement of the stand is guided and supported by a guide member 18' preferably formed of heavy wire, and having one end connected with the bolt 19 that extends transversely through the projecting end 2 of the board 1 to support the bracket 6 therein, while the other end extends outwardly, then beneath the board being connected at its extremity therewith. 20 The stand 16 is provided with a handle 18 on its under side so that movement thereof is facilitated.

This type of ironing board is provided with a supplemental smaller board 19' that is adapted to be positioned in superposed relation above the main board 1 as is clearly shown in Fig. 1 of the drawings. The supplemental board 19 is connected with the main board by a substantially U-shaped bracket 20 having its base portion secured to a projecting portion of the board 19' at one end thereof, and said sides of the bracket extend downwardly and have their extremities mounted on the transverse bolt 19 through the projecting portion of the main board 1. These extremities are pivotally mounted on the bolt so that the supplemental board 19' is adapted to be hingedly connected with the main board, so that when 45 not in use it may be swung outwardly so as to be out of the way. The board 19' is provided on its underside with a strengthening brace 21 that acts as a spacing member and which rests upon the top of the board 1 when 50 the supplemental board is in operative position as is clearly shown in Fig. 1 of the accompanying drawings.

In operation, when the various parts of the portable ironing board are positioned as 55 is clearly shown in Fig. 1 of the drawings, it is obvious that the main board 1 will be securely supported in position and with no likelihood of the supporting means becoming loosened. The operation of the iron support is simple as when it is desired to 60 use the same it is swung outwardly by grasping the handle 18 its movement being addi-

tionally guided and strengthened by the guide wire 18'. When it is not desired to use the supplemental board 19' the same is 65 adapted owing to its pivoted connection with the main board 1 to swing outwardly so as to be out of the way. When it is desired to fold the board, the support 5 is first 70 swung upwardly beneath the board 1 and then the pivoted brace 12 is engaged with the spring clasp 15 thereby engaging and holding the support 5 beneath the board, and then the supporting leg 4 is swung upwardly and engaged with the spring clip 15 75 whereby all of the supporting parts of the board will be folded beneath the same so as to form a very compact device of this character when folded that may be easily transported from place to place. This type of 80 ironing board forms a very efficient portable device of this character and the various accessories connected therewith will increase the efficiency of this type of article.

From the foregoing description taken in 85 connection with the accompanying drawings, it is thought that a clear and comprehensive understanding of the construction, operation, and advantages of the invention may be had, and while I have shown and 90 described the device as embodying a specific structure, I desire that it be understood that such changes may be made in said structure as do not depart from the spirit and scope of the invention as claimed.

Having fully described my invention, what I claim as new, and desire to secure by Letters Patent, is:

The combination with an ironing board, of a support having its upper ends pivotally 100 connected with the end portion of the board, a second support having legs pivotally mounted intermediate the length of the board and extending in cross relation to the first support when in a set up position, a 105 cross bar connecting the legs and engaging the first support when the second support is in a set up position, the second support when in a folded position resting flat against the ironing board, a brace pivotally connected 110 with one end of the ironing board and engaging the first support when in a set up position and engaging the cross bar when in a folded position to retain the second support in a folded position, and a clip carried 115 by the ironing board for engaging the brace to retain the brace in a folded position, the first support when in a folded position engaging the brace and being engaged by the clip.

In testimony whereof, I affix my signature hereto.

THOMAS McCULLOUGH.
